CLAIM

The ornamental design for a ceramic cutting wheel, as shown and described.

DESCRIPTION

Fig. 1.1 is a front-top-right perspective view of a first embodiment of a ceramic cutting wheel showing my new design;

Fig. 1.2 is a front elevation view thereof;

Fig. 1.3 is a rear elevation view thereof;

Fig. 1.4 is a right side elevation view thereof;

Fig. 1.5 is a left side elevation view thereof;

Fig. 1.6 is a top plan view thereof;

Fig. 1.7 is a bottom plan view thereof;

Fig. 2.1 is a front-top-right perspective view of a second embodiment of a ceramic cutting wheel;

Fig. 2.2 is a front elevation view thereof;

Fig. 2.3 is a rear elevation view thereof;

Fig. 2.4 is a right side elevation view thereof;

Fig. 2.5 is a left side elevation view thereof;

Fig. 2.6 is a top plan view thereof; and

Fig. 2.7 is a bottom plan view thereof.

The evenly spaced broken lines in the figures depict portions of the ceramic cutting wheel that form no part of the claimed design. The long-dash, short-dash lines represent the unclaimed boundary of the claimed design.
